UNITED STATES PATENT OFFICE

JAMES B. SLINN, OF BONAPARTE, IOWA

AIRPLANE WING

Application filed June 24, 1927. Serial No. 201,179.

The invention relates to improvements in airplane wings.

The objects of the invention are to provide an airplane wing that is perfectly safe and stable within itself, one that is free of erratic tendencies and amendable to control under all conditions, to simplify the construction by using but few parts, to make the wing lighter and yet stronger than those of which I am aware, and easy to standardize or modify to meet desired requirements, and to provide an airplane wing that has great lift, that has little resistance, forms a good glider, a proper tendency to stay in the air, and that provides a quick take off.

One form of the invention is illustrated in the accompanying drawings in which Figure 1 is a plan of one form of an entire wing.

Figure 2 is a front elevation of the same. Figure 3 shows in perspective one-half of a wing with parts shown in cross section at about the middle of the wing's length. Figure 4 shows in perspective the framework only of part of a wing. Figure 5 is a cross section of a wing showing the angular contour and a form of bracing.

Figure 6 is a cross section of a wing illustrating the manner of constructing it with but one beam, and Figure 7 illustrates a flat form of wing having a camber in the center of its lower surface.

The wing comprises a rectangular frame made up of end rails 5, but one of which is shown in Figure 4, joining which are side rails 3, 4 forming the front and aft edges of such wing. Connecting the said side rails 3, 4 at spaced intervals are cross members or ribs 2 substantially paralleling the end rails 5. Overlying said cross members or ribs 2, and reaching from end to end of the wing is a pair of upper beams 1 substantially paralleling the rails 3, 4 and spaced with reference to the latter and to each other about in the proportion shown in Figure 3, while directly beneath each beam and paralleling the same is an auxiliary beam 11. In addition to these I may employ a diagonal brace 10, Figure 4, joining one of the upper beams 1 at about the middle of its length with the other beam 1 near its outer end. The frame thus

provided may be covered above and below with any desired material, the upper portion of which is indicated at 7 and the lower portion at 8. In Figures 3, 4 and 5 it will be observed that the forward beam 1 is of somewhat greater height than the rear one, while in Figure 7 both are of about an equal height.

The covering material conforms to the contour of the structure and therefore from the forward edge at 3, Figures 3 and 5, it is inclined upwardly upon the leading beam 1 thence at a slight angle downwardly to the rear beam, in one form of the wing, and thence again at an angle downwardly to the rear edge at 4, following back beneath the wing over the lower beams 11.

In some of the claims the use of the terms "longitudinal" and "longitudinally" designate the longest measurement of the wing although such terms when applied to airplanes usually mean the fore and aft direction. This is stated merely in the interest of a clear understanding of meaning.

Referring to the crosswise section Fig. 5, it will be seen that the contour fore and aft of this airplane wing is based on angles and straight lines. These angles and straight lines are the basic principle of this invention. Experiments have proved they are fundamental in securing automatic stability, lift, minimum resistance and control. The surfaces 7 and 8 resting on beams 1 and auxiliary beams 11 are a factor of this arrangement in the efficiency of the wing, the angles formed running from tip to tip of wing give great lift and stability. These angles may be modified or changed to meet requirements of ratio aspect of wing. This is done by moving beams 1 or beam 1 backward or forward. The front margin presents a bevel cutting edge offering little or no resistance, on the contrary it seems to aspirate or move against the wind. The auxiliary beams 11 excepting those which are a part of main beams 1, illustrated by Fig. 5, may be used and refined as requirements demand. The material used in constructing wing may eliminate them entirely.

The ribs 2 lying between main beam 1 and auxiliary beam 11 may be any number or

shape to give proper strength and refinement, and these form with the latter a truss, giving great strength and rigidity to the wing, the whole at the same time being relatively light in weight.

5 The marginal rails 3 and 4 are attached to the ends of the ribs 2, and the marginal end rails 5 are attached to the beams 1 and auxiliary beams 11 in any suitable manner, the ends of the beams being tapered to conform to the smaller cross section of the said rails 5 to constitute a finished appearance at the wing ends.

10 A self-supporting or cantilever wing may be made by increasing depth of wing at center, the beams 1, 11 may be beveled above or below, and the wing may be any length or any width found expedient, and of plan any contour.

15 20 The ailerons shown in Fig. 1 and Fig. 3 are given to show how they may be attached or used, either let into the wing as in Fig. 1 or hinged to rear edge of wing as in Fig. 3.

Having thus described my invention, what 25 I claim as new and desire to secure by Letters Patent is:—

1. An airplane wing including a framing forming the body thereof having extensions projecting from opposite sides in two spaced 30 positions disposed longitudinally thereof in spaced relation to and substantially paralleling the longitudinal edge thereof, and a covering for the structure, the same presenting substantially straight surfaces between the 35 members and the said edges of said frame.

2. An airplane wing including a substantially flat framing forming the body thereof, two members extending from opposite surfaces of the framing disposed longitudinally 40 thereof in widely spaced relation, one being spaced from the leading edge and the other being spaced from the aft edge of the frame and substantially paralleling the named edges, and a covering for the structure presenting substantially straight surfaces between the 45 said members and between the latter and the said leading and aft edges.

3. In an airplane wing, a framing forming the body of said wing, and a projection at 50 each side of the framing extending longitudinally of the latter at two spaced positions and substantially paralleling an edge of the same, each forming ridges along said wing extending from the plane of the same, and a 55 covering enclosing the frame and the projections.

4. In an airplane wing, a flat framing forming the body of said wing, a pair of members at each side of and projecting from the framing disposed longitudinally thereof and paralleling the longest edge of the wing, the members of each pair being spaced from each other, and each spaced from one of the edges 60 of the frame, and a covering enclosing the 65

structure, the same presenting substantially flat surfaces over the same.

5. An airplane wing including in its construction a flat frame comprising longitudinal members and end members, the said longitudinal members forming the front and rear edges of said wing, cross ribs spaced from each other and connecting at their ends the said longitudinal members, a pair of beams extending longitudinally of the frame upon its top, the same being spaced from each other and from the front and rear edges of the frame, the same overlying the said end members and the said ribs and secured to the same, and a pair of beams secured upon the lower side of the frame substantially in the same position as the first named pair.

6. An airplane wing including in its construction a flat frame comprising longitudinal members and end members, the said longitudinal members forming the front and rear edges of said wing, cross ribs spaced from each other and connecting at their ends the said longitudinal members, a pair of beams extending longitudinally of the frame upon its top, the same being spaced from each other and from the front and rear edges of the frame and extending to the said end members and overlying the said ribs and tapered at their ends on their upper surfaces to substantially conform to the said end members.

7. An airplane wing including in its construction a flat frame comprising longitudinal side members and end members, the said longitudinal members constituting the front and rear edges of the wing, cross ribs spaced from each other and connecting the said longitudinal members, a pair of beams extending longitudinally of the frame upon its top and spaced from each other and from the front and rear edges of the frame and also extending to the said end members and overlying the said ribs, the beam lying nearest the said rear edge of the frame having a less height than the forward beam.

8. An airplane wing including a main frame parts of which constitute the margins of the wing, a series of ribs extending transversely within the frame and secured to the fore and aft members thereof, and a pair of beams on the upper and lower sides of the frame extending longitudinally of the same crossing the said ribs and secured thereto and substantially paralleling the said fore and aft members.

9. An airplane wing including a main frame parts of which constitute the margins of the wing, a series of ribs extending transversely within the frame and secured to the fore and aft members thereof, a pair of beams on the upper and lower sides of the frame extending longitudinally of the same crossing the ribs and secured thereto and substantially paralleling the said fore and aft members,

and a brace extending diagonally of the frame between and secured to said beams.

10. An airplane wing comprising a main frame parts of which constitute the margins 5 of the wing, a series of ribs extending transversely within the frame and secured to the fore and aft members thereof, a pair of beams on the upper and lower sides of the frame extending longitudinally of the same crossing 10 the ribs and substantially paralleling the said fore and aft members, and a covering enclosing the structure, said covering presenting substantially flat surfaces bridged between the several beams and the said fore and aft 15 members.

11. An airplane wing comprising a framing the member of which form the margins of said wing, transverse ribs extending between the fore and aft members of the frame, 20 a pair of beams lying upon the upper surface of the frame extending from end to end thereof substantially paralleling the said fore and aft members, a pair of beams on the under surface of said frame also extending from end 25 to end thereof and substantially paralleling the fore and aft members, and a covering enveloping the structure, the same bridging between the several beams and bridging between the beams and the said fore and aft 30 members.

12. An airplane wing having a narrow leading edge and a narrow rear edge and including a pair of extensions projecting each side of the plane in which the edges lie, the 35 same substantially paralleling said edges and spaced therefrom and from each other and extending from end to end of the wing, one of the extensions, or that lying nearest the rear edge of the wing being of lower height than 40 the other, and a covering enveloping the edges and the extensions and presenting flat surfaces between the parts over which they extend.

13. An airplane wing having a comparatively thin leading edge and a thin rear edge, the said edges and wing tips all lying in one plane, said wing at its upper surface having a straight surface inclined at an angle upwardly and rearwardly from its leading edge, 45 and at its lower surface having a straight surface inclined downwardly and rearwardly from said leading edge at a much less angle, the lower surface of the wing rearward thereof substantially paralleling said plane, the 50 upper surface of the wing rearward of the angular portion extending toward said plane as the rear edge of said wing is approached.

14. An airplane wing having a comparatively thin leading edge and a thin rear edge, 60 the said edges and wing tips all lying in one plane, said wing at its upper surface having a straight surface inclined at an angle upwardly and rearwardly from its leading edge, and at its lower surface having a straight surface inclined downwardly and rearwardly 65

from said leading edge at a much less angle of inclination, the lower surface of the wing rearward thereof substantially paralleling said plane, the said upper surface of the wing rearward of the angular portion and the rearward portion of the lower surface both extending toward said plane as the wing's rear edge is reached.
